UNITED STATES PATENT OFFICE

167,449

PLATE OR SIMILAR ARTICLE

Helen M. Dost, Glenview, Ill., assignor to Onondaga Pottery Company, Syracuse, N. Y., a corporation of New York

Application May 6, 1952, Serial No. 19,614

Term of patent 14 years

(Cl. D44—15)

To all whom it may concern:

Be it known that I, Helen M. Dost, a citizen of the United States, residing at Glenview, Cook County, State of Illinois, have invented a new, original, and ornamental Design for a Plate or Similar Article, of which the following is a specification, reference being had to the accompanying drawing, forming a part hereof.

The sole figure is a top plan view of a plate or similar article, showing my new design. The characteristic feature of the design resides in the annular ring comprising the repeating floral design, as shown.

I claim:

The ornamental design for a plate or similar article, as shown and described.

HELEN M. DOST.
